Specification for Design.

Patented Oct. 24, 1916.

Application filed July 31, 1916. Serial No. 112,470. Term of patent 14 years.

To all whom it may concern:

Be it known that I, RICHARD GRIFFITH, a citizen of the United States, residing at Akron, Ohio, have invented a new, original, and ornamental Design for a Sign or Similar Article, of which the following is a specification, reference being had to the accompanying drawing, forming a part thereof.

The figure is a perspective view of a sign illustrating my new design.

Copies of this patent may be obtained for five cents each, by addressing the "Commissioner of Patents, Washington, D. C."

I claim:

The ornamental design for a sign or similar article, as shown.

In testimony whereof, I affix my signature.

RICHARD GRIFFITH.
